RADIO ANTENNA

Lawrence A. Hyland, Washington, D. C., assignor,
by mesne assignments, to Bendix Radio Corporation,
New York, N. Y., a corporation of Delaware

Application December 19, 1935, Serial No. 55,256

1 Claim. (Cl. 250—33)

This invention relates to radio antennas generally. More particularly this invention relates to radio antennas adapted for aircraft.

An object of this invention is to provide an antenna for aircraft adapted to be carried in a convenient and out-of-the-way position.

Another object of this invention is to provide an antenna for aircraft adapted to be mounted in a readily accessible position.

10 Still another object of this invention is to provide an antenna for aircraft in an exposed position presenting very little wind or air resistance during flight.

15 A further object of this invention is to provide an antenna for aircraft in a position where its signal pick-up efficiency is substantially unimpaired yet where it is not exposed to damage or view and where it offers substantially no additional wind or air resistance.

20 Other and further objects of this invention will be apparent to those skilled in the art to which it relates from the following specification and the claim.

25 In accordance with this invention I provide an antenna for aircraft, mounted in a convenient and efficient manner in a position directly behind the propeller or propellers of the aircraft. This is accomplished by coiling the antenna up into the coil of wire sufficiently large 30 to fit the outer guard or Townend ring surrounding the aircraft engine. The antenna may be in the form of a closed loop and it may be enclosed in a metal shield or any other type of shield, not metal, suitable to protect the antenna 35 conductor from weather or damage.

Further details of this invention are set forth in the following specification and the drawing in which, briefly, Figs. 1 and 1a illustrate an embodiment of this invention; Fig. 2 shows a 40 sectional view of the antenna and mounting taken along the line 2—2 of Fig. 1; Fig. 3 shows a fragmentary view of a section of the antenna taken along the line 3—3 of Fig. 5; Fig. 4 shows a sectional view of the antenna casing coupling; 45 and Fig. 5 shows a section of the Townend ring and the manner in which it is split by insulation.

50 Referring to the drawing in detail, reference numeral 1 designates a cover, referred to as the Townend ring, employed over aircraft engine cylinders for streamlining effect. This cover is mounted over the aircraft engine and may extend over the engine exhaust manifold 3 back to the fuselage 2 or other engine mounting means such 55 as a nacelle set into a wing section. The propeller

shaft 4 extends to the front of the cover 1. This cover 1 may be made in various shapes and sizes and the design thereof must necessarily be made to fit the type of aircraft with which it is intended to be used. 5

The antenna casing 5 is mounted on the interior of the engine cover 1 and is supported in fixed relation thereto by suitable means, such as cement 7, or it may be sprung into place inside of the ring 1 and held there by its own resilience. 10

Suitable straps and bolts may be used to fasten the casing 5 to the engine cover 1 where desired. The cover 1 also may be provided with a slight groove, which will not interfere materially with its streamlining properties, to receive 15 the tubular member 5.

Where the tube 5 is of metallic material a layer 20 of insulation, such as phenol condensation products and the like is employed to space this tube from the metal cover 1.

The cement 7 is also preferably of insulation material made of suitable resin solutions and the like. 25

Electrical conductors 10 forming the antenna, are mounted in spacers 9 of porcelain or other 30 suitable materials, inside of the tube 5. These conductors are all joined together to form a series of turns of the loop antenna in cases where the antenna is a closed loop. The ends of the closed loop are brought out of the tube 5 through 35 the auxiliary or lead-in tube 6, which may be made of metallic material and welded, soldered or otherwise attached to the tube 5.

It is, of course, obvious that the tube 5 may be made of insulation material, such as, hard 35 rubber, phenol condensation products or similar more or less plastic materials. Or, if desired, the tube 5 may be made of metals, such as, aluminum, copper, zinc and/or alloys of these and other metals and the outside of the tube may 40 be given a relatively heavy or thick coating of an insulating varnish, lacquer, resin or similar substance.

The lead-in 6 may be taken from the bottom 45 of the antenna coil instead of the top as shown and the ends of the tube 5 coupled together at the bottom by a suitable grommet or sleeve 11 which receives the ends of the tube 5 as shown in Fig. 3. The joints between the tube 5 and the sleeve 11 are preferably sufficiently tight to 50 prevent water from entering the tube. The sleeve 11 is provided with a projecting tube 11a also made of elastic material, such as rubber and the like, for receiving the lead-in conductor shield 6 which houses the lead-in conductors 12. 55

A strip of insulation material 13 of phenol or resin condensation products, ceramic materials and the like is riveted, screwed, or otherwise attached to the ring 1 as shown in Figs. 1a, 3, 4, 5 and 5. Two rows of rivets 14 are used to attach the strip 13 to the ends of the split ring one to hold these ends firmly to the strip. The purpose of splitting the Townend ring 1 is to destroy its effect as a signal screen or shield 10 for the loop antenna. The antenna being placed inside of the ring, as shown in Figs. 1 and 1a, does not destroy the streamlining effect of the latter and, inasmuch as the ring is split by an insulation member eddy currents are prevented 15 from circulating around the ring 1.

While I have described an embodiment of this invention in detail, it is, of course, apparent that modifications within the scope and spirit of the invention may be made and, therefore, I do not 20 desire to limit the invention to the exact details

set forth except insofar as they are defined by the following claim.

What I claim and desire to secure by Letters Patent of the United States is as follows:

An antenna for aircraft comprising a coil of 5 conducting turns adapted to intercept signaling energy, a tubular metal casing formed into a split ring for enclosing said coil of conducting turns, insulation means for insulating the turns of said coil from said metal casing, a metallic 10 streamlining member surrounding the outer extremities of the cylinders of a radial aircraft engine, said streamlining member being formed into a split ring, insulation means attached to the ends of said split streamlining member and 15 means for supporting said coil of conducting turns in said streamlining member to permit said coil of conducting turns to intercept signaling energy.

LAWRENCE A. HYLAND. 20
